LABORATORY TURBIDIMETER

Michael D. Buck, Ames, Iowa, assignor to Hach Chemical Company, Ames, Iowa, a corporation of Iowa

Filed Nov. 12, 1965, Ser. No. 88,075

Term of patent 14 years

(Cl. D16—2)

FIGURE 1 is a perspective of a turbidimeter embodying my new design;

FIG. 2 is a front elevation of the turbidimeter shown in FIG. 1; and

FIG. 3 is a side elevation of the turbidimeter shown in FIG. 1.

Both sides of the turbidimeter are identical and the rear of the instrument is plain.

I claim:

The ornamental design for a laboratory turbidimeter, substantially as shown and described.
